CHAIN GRATE STOKER

Filed Aug. 20, 1926

UNITED STATES PATENT OFFICE

HOWARD J. KERR, OF WESTFIELD, NEW JERSEY, ASSIGNOR TO THE BABCOCK & WILCOX COMPANY, OF BAYONNE, NEW JERSEY, A CORPORATION OF NEW JERSEY

CHAIN GRATE STOKER

Application filed August 20, 1926. Serial No. 130,370.

This invention relates to a chain grate stoker that may be cooled by air, and this air may afterwards be used for combustion purposes in a furnace. The invention will be understood from the description in connection with the accompanying drawing, in which a vertical section of an illustrative embodiment of the invention is shown.

In the drawing, reference character 1 indicates the lower portion of a furnace that is shown broken away. A chain grate stoker having an upper run 2 and a lower run 3 is located below the furnace chamber proper, in the usual manner, and the chain grate 5 stoker passes over sprockets that are mounted on a driving shaft 4 and a driven shaft 5, in the manner well known in this art. Transverse I-beams 6 extend across the furnace below the upper run 2 of the chain grate, and support the same. Plates 7 are pivoted to the lower flanges of the I-beams 6, and these plates rest upon the upper side of the lower run 3 of the chain grate stoker, so that the I-beams 6 and plates 7 divide the space between the runs of the stoker into compartments, into which combustion air may be introduced, and thence pass upwardly through the upper run of the chain grate stoker in a manner well known.

30 A drag plate 8 is located below the lower run 3 of the chain grate stoker, and is supported by transverse I-beams 9, so that the lower run of the stoker will pass along the upper surface of the drag plate 8. Baffles 10 extend upwardly from the bottom plate 11 and are located between the I-beams 9 with their upper edges extending some distance above the lower edges of these I-beams. The bottom plate 11 may be provided with a plurality of openings having cover plates or doors 11' through which dust and soot may be withdrawn. Some of the I-beams 9, for example, the first and last ones of the series, may be provided with holes 12 in the webs 45 thereof.

Air is admitted to the space 13 in any convenient manner, as by openings in the front plate as illustrated. The space 13 is located near the front of the furnace casing 50 beneath the hopper 14, and also beneath the

sprocket on the driving shaft 4. The rear ends of the plates 8 and 11 are connected by a transverse plate, and one or more outlets 15 extend from this plate to a header 16 that is connected to a suction fan 17, the outlet 18 of which may lead to the furnace.

The operation is as follows: Coal is fed by means of the hopper 14 upon the upper run 2 of the chain grate stoker, and is carried toward the left, as indicated in the drawing, 60 into the lower portion of the furnace where it is ignited, the ashes and clinker being carried to the rear end and falling into the ashpit in the usual manner. The lower run 3 of the chain grate stoker passes along the drag plate 8, carrying siftings toward the right, and finally over the right-hand end of the drag plate 8, from which they fall into the ashpit. Air entering the space 13 passes in part through the openings 12 in the webs of the I-beams 9, and in part below the lower edges of these I-beams, and over the upper edges of the baffles 10 in a sinuous path, as indicated by the arrows, thus impinging against the lower side of the drag plate 8 and cooling the same, as well as cooling the links of the lower run 3 of the chain grate stoker as the heat therefrom is transmitted through the plate 8. The air passes 70 in a direction countercurrent to the direction of travel of the lower run 3 of the chain grate stoker, and becomes more and more heated until it passes out through the outlets 15, header 16, fan 17 and outlet 18, 75 into the furnace, where the heated air is used for combustion purposes.

Dust and soot that may enter with the air are thrown out between the baffles 10 and settle on the plate 11, from which they may be withdrawn at intervals through the doors 11'. The fan 17 in drawing the cold air longitudinally through the space between the plates 8 and 11 causes a slight suction at the front end of the stoker. This decreases the tendency for dust to escape from the furnace, thus keeping the boiler room clean. As air is drawn in through small crevices that frequently occur in the front casing of stokers, this avoids the objection that frequently occurs, because pressures greater than 100

atmospheric inside the furnaces often cause dust to be forced out through crevices. On the contrary, the decreased pressure produced by this device causes the air to be drawn inwardly and prevents dust and ashes from escaping into the boiler room.

I claim:

1. In a furnace provided with a chain grate stoker, a drag plate for the lower run of said stoker, transverse I-beams to support said drag plate, some of said I-beams being provided with holes through the webs thereof, and means to pass air into contact with the lower side of said drag plate and through said holes.
2. In a furnace provided with a chain grate stoker, a drag plate for the lower run of said stoker, means to pass air longitudinally beneath said drag plate in a stream, and means to direct said stream at intervals against said plate.
3. In a furnace, a chain grate stoker, a duct extending longitudinally of said stoker for substantially the entire length thereof and beneath the lower run thereof, means for passing air through said duct, and a plurality of baffles on the lower wall of said duct to direct the air passing therethrough against the upper wall.
4. In a furnace provided with a chain grate stoker, a drag plate for the lower run of said stoker, transverse supports for said drag plate, a bottom plate disposed beneath said drag plate and spaced therefrom to form a duct, baffles disposed in said duct between said supports and cooperating with the supports and plates to form a sinuous path, and means to pass air along said path into contact with the lower side of said drag plate.
5. In a furnace provided with a chain grate stoker, a drag plate for the lower run of said stoker, transverse supports for said drag plate, a plate disposed beneath said drag plate and spaced therefrom, baffles disposed between said supports and forming with the supports and plates a sinuous path, means to pass air along said path into contact with the lower side of said drag plate, and means whereby soot and dust may be removed from between said baffles.
6. In a furnace, a chain grate stoker, a duct extending longitudinally of said stoker and beneath the lower run thereof, the top of said duct contacting with said lower run, an inlet and an outlet disposed at opposite ends of said duct, and means for passing a cooling fluid through the duct from the inlet to the outlet.
7. In a furnace, a chain grate stoker, a duct extending longitudinally of said stoker and beneath the lower run thereof, the top of the duct contacting with said lower run, an inlet for said duct disposed near the front of the stoker and an outlet therefor disposed near the rear of the stoker, and means for

passing air through said duct from the inlet to the outlet.

8. In a furnace, a chain grate stoker, a duct extending longitudinally of said stoker and beneath the lower run thereof, the top of the duct contacting with said lower run, an inlet for said duct disposed near the front of the stoker, and an outlet therefor disposed near the rear of the stoker, and means for passing air through said duct from the inlet to the outlet, said means being disposed at the outlet end of the duct.

HOWARD J. KERR.
